[57] **CLAIM**

The ornamental design for an audio recorder/player for video cassette tapes, as shown and described.

DESCRIPTION

FIG. 1 is a front elevational view of an audio recorder/player for video cassette tapes showing my new design; FIG. 2 is a left side elevational view thereof; and, FIG. 3 is a top plan view.

The right side elevational view, the rear elevational view and the bottom plan view are plane and unornamented.

FIG. 1

FIG. 2

FIG. 3
